TOILET SEAT

Cyril T. Krenzer, Rochester, N. Y., assignor to
 Electric Steam Sterilizing Company, Inc., New
 York, N. Y., a corporation of Delaware

Application August 13, 1940, Serial No. 352,351

12 Claims. (Cl. 4—233)

My invention relates to toilet seats of the class that are mounted upon or above a suitable bowl and are intended to be raised or lowered as occasion requires, for use, cleansing or sterilization; and objects of my invention are to provide automatic means for lowering and raising the seat; to make the operation of such automatic means positive and accurate; to prevent disarrangement of the seat operating mechanisms by manual interference with the seat; to provide for the sterilization of the seat at proper times; and to secure the other novel advantages hereinafter pointed out and explained.

In the drawings, Fig. 1 is a front elevation showing the seat halves raised, portions including the upper ends of the seat halves and case being broken away; Fig. 2 is a front elevation showing the seat lowered and broken off, and the front casing removed; Fig. 3 is a vertical, sectional view taken as looking to the right on Fig. 2, the case and front plate being shown in section; Fig. 4 is another vertical sectional view, taken as on line 4—4 of Fig. 2 looking to the right; Fig. 5 is a vertical sectional view taken on the line 5—5 of Fig. 2 looking to the right; Figs. 3, 4 and 5 are on a somewhat reduced scale; Fig. 6 is a cross sectional view, on a slightly enlarged scale, taken on the line 6—6 of Fig. 2 looking down; Fig. 7 is a vertical sectional view, on a slightly enlarged scale, taken on the line 7—7 of Fig. 2 looking to the right; Fig. 8 is a much enlarged detail taken on the line 8—8 of Fig. 2, looking down; Fig. 9 is a cross sectional detail, much enlarged, on line 9—9 of Fig. 2; Fig. 10 is a detail, much enlarged, taken as on line 10—10 of Fig. 2, looking down; Fig. 11 is a perspective view, on a much enlarged scale, of motor control mechanism; Fig. 12 is a perspective view, on a much enlarged scale of switch control mechanism; Figs. 13 and 14 are elevational details of 40 the switch control mechanism of Fig. 12, showing it in different positions; Fig. 15 is an elevational detail on a reduced scale, of the mechanism for preventing manual interference with the automatic seat raising mechanism; and Fig. 16 is a diagrammatic showing of the electrical circuits employed in the operation of the mechanism.

Similar parts are designated by similar reference numerals in all the figures.

The seat and its operating mechanism are preferably mounted upon a conventional bowl 1, the mechanism being assembled within a case 2, provided with a back, sides and bottom and a detachable face plate 3, suitable supports being pro-

vided within the case for mounting the elements of the mechanism.

The halves 4, 5, which constitute the seat, are fixed upon a common axle 8 carried by suitable bearings 9, 10 in the base of the case 2, the axle having a crank arm 11 fixed upon it, by means of which the axle 8 may be turned by means of an electric motor to lower and raise the seat as will now be explained.

A relay coil 15, is adapted, when energized, to shift an armature 16 to retract a brake band 17 controlling a fly wheel 18, driven by much reduced gearing (not shown, as the construction is conventional) actuated by the shaft 19 of a motor 20, which is simultaneously thrown into circuit from the coil 15 by the brake member 17 as will be hereinafter traced.

The movement of the motor 20 causes the crank disk 30 to revolve clockwise, carrying up the connecting rod 31, which, by a ball and socket connection 32 at its upper end with an arm 33, rocks upward the arm 33 on a fixed pivot 34, thereby causing the spring connections 35, 36 between the opposite ends of the arm 33 and the ends of a cross bar 37 on an arm 38, also carried by pivot 34, to rock the arm 38 so as to depress its end 39, to which a pitman rod 40 is connected by a ball and socket joint, and causing that rod to turn the crank arm 11 on axle 8, swinging the seat down toward but not quite to the bowl, as shown by solid lines in Fig. 3.

A cushioning action is provided for by a spring 43 engaged by an arm 44 keyed to shaft 8, and also by a spring anchored within the case and connected by a strap 46 with a collar 47 keyed to shaft 8.

A bar 50 is mounted to slide in guides 51, 52 in the casing, its upper end embracing the arm 38 between antifriction rollers 53, 54, so that the bar may be carried up and down by the arm without binding.

The bar 50 carries a pin 55 and an arm 56 the functions of which will be hereinafter explained.

A contact control 59 is mounted to slide in the case, being held to duty by a headed pin 60 passing through a slot in it and into the case, and being normally pressed inwardly by a spring 61 behind it. This control lies below a contact arm 62 which it may be made to close with contact 63 by being rocked on the pin 60, as shown in Fig. 14. The mere sliding of control 59 to and fro will not close the contacts. But its rocking will do so.

When the bar 50 is depressed sufficiently its

arm 56 will engage a contact element 64 and close a circuit as will be hereinafter described.

The operation of the mechanism is as follows:

When the apparatus is in normal, initial position the seat is raised and operation may be initiated by closing an electrical circuit so as to start the motor 20. This may be done by closing the circuit manually or otherwise, as by a push button 70, establishing a circuit from source through lines 71, 72, relay 15, and line 74 back to source, energizing the relay 15 and causing it, through armature 16, to release brake 17 and close contacts 21, 23, and 22, 24, making a circuit through lines 71, 21, 23, 76, motor 20 and lines 78, 74 back to source, and starting the motor, and also closing a circuit through lines 71, 79, contacts 22, 24, line 80, contacts 81, 82, lines 83, 72; through relay 15 and line 74 back to source, keeping the relay energized to hold the brake 17 released and the contacts 21, 23 and 22, 24 closed.

The action of the motor 20 turns the crank disk 30, raising the connecting rod 31, rocking the arms 33, 38 pushing down the pitman rod 40, which through crank arm 11 rotates the shaft 8, bringing the seat down into the position shown by the solid lines in Fig. 3, when the projection 87 on disk 30 passing under the end of arm carrying contact 81, opens contacts 81, 82, breaking the circuits and stopping the motor.

The momentum of the mechanism will cause projection 87 to clear the arm of contact 81.

If now it is attempted to manually raise the seat, that can not be done successfully; because the upward movement of the seat, turning the seat axle 8 and pushing up the pitman rod 40, will simply cause the arm 38 and its cross head 37 to rock on the pivot 34 stretching spring 36 and compressing spring 35 without disturbing arm 33, which is held by connecting rod 31 and the motor against backward movement, so that the seat will not remain raised but will, when released, be swung down again by the action of the springs 35, 36. This is illustrated in Fig. 15.

With the seat lowered into the position slightly above the bowl it is ready for use by being sat upon, the weight of the user pushing down the seat until its free ends rest upon the bowl. This movement rotates the axle 8 slightly increasing the tension of spring 45 and the compression of spring 43 so that the tendency of the seat to rise, which it is normally somewhat overbalanced to do, will be increased to such an extent that, on the user rising, the seat will be raised by the springs.

The upward movement of the seat when released causes contacts 62 and 63 to close completing circuits through relay and motor and putting the motor in action, causing the crank disk 30 to revolve, drawing down connecting rod 31, rocking arms 33, 37, raising pitman rod 40, and turning axle 8 backward to fully raise the seat, at the completion of which movement the projection 87 opens contacts 81, 82 and stops the motor.

The final upward travel of the bar 50 carries its pin 55 past the end of sliding element 59 which is pressed forward by spring 61 into the position shown in Fig. 13, so that the end of 59 is below the pin when the seat is fully down. And when the seat is released to rise, the descending pin 55 will rock the element 59 so as to throw up its outer end against projection 89 on contact arm 62, causing it to close with contact 63 and maintaining the actuating circuit, and until the contacts 21, 23 and 22, 24 are established, as before explained.

As the seat reaches its fully raised position 75

arm 56 engages element 64, thereby closing contacts 81, 82 and establishing a circuit from source through lines 71, 83, contacts 81, 82, lamp starting control 84, ultra violet ray or other selected lamp 85, and lines 86 and 74 back to source; so that the seat may be sterilized, by rays from the lamp, while the seat is raised. And when the seat starts to descend the connection 81, 82 is broken and the lamp extinguished, so that there will be no rays from it except when the seat is fully raised.

It will be seen, therefore, that when the cycle of operation of the apparatus is once started, as by pushing the button 70, the seat will be lowered automatically and ready for use, and that after use it will be raised automatically to its initial position in which it will be sterilized, as by ultra violet rays, or other suitable sterilizing agents, the action of which will be automatically discontinued when a new cycle of operation of the lowering and raising means is initiated. This arrangement entirely eliminates manual contact by the user with the seat, thus avoiding danger of contamination through handling, or disarrangement of the mechanism by careless interference by thoughtless or careless users.

I wish it to be understood that what I have illustrated and described is to be regarded as a typical but not an exclusive embodiment of my invention; for the precise mechanism may be changed as by the use of mechanical equivalent, or otherwise without departing from the spirit of my invention or the scope of my claims.

Having thus described my invention, what I claim and desire to secure by Letters Patent of the United States is:

1. The combination, with a support, of a toilet seat fixed on a rotatable shaft mounted on the support, electrically propelled means, having a fixed, irreversible direction of rotary movement, and automatically actuated means for converting said rotary movement into alternating reversals, whereby the shaft is turned in one direction to lower the seat and in the opposite direction to raise it.

2. The combination, with a support, of a toilet seat fixed on a rotatable shaft mounted on the support, electrically propelled means, having a fixed, irreversible direction of rotary movement, and automatically actuated means for converting said rotary movement into alternating reversals, whereby the shaft is turned in one direction to lower the seat and in the opposite direction to raise it, and adjusting means functioning between reversals of the shaft to change the direction of its rotation.

3. The combination, with a support, of a toilet seat hinged upon the support, electrically propelled means having an irreversible direction of rotary movement, and connecting means embodying a compound rocking bar having two commonly pivoted arms connected by springs for changing such movement into reversals to successively lower or raise the seat, the compound rocking bar being yieldable on its pivot to prevent transmission of retrograde movement to the electrically propelled means.

4. The combination, with a support, of a toilet seat hinged upon the support, electrically propelled means having an irreversible direction of rotary movement, and connecting means embracing a bar carried by a fixed pivot, a T bar carried by the same pivot and springs connecting the arms of the T bar to the free end of the first mentioned bar, whereby movement of that

bar may be transmitted to the T bar through the springs for changing such movement into reversals to successively lower or raise the seat.

5. The combination, with a support, of a toilet seat hinged upon the support, electrically propelled means, having an irreversible direction of rotary movement, and connecting means embracing a bar carried by a fixed pivot, a T bar carried by the same pivot and springs connecting the arms of the T bar to the free end of the first mentioned bar, whereby the movement of that bar may be transmitted to the T bar through the springs, the direction of movement of the first mentioned bar being irreversible by the T bar, for changing such movement into reversals to successively lower or raise the seat.

6. The combination, with a support, of a toilet seat mounted thereupon, an electric motor provided with speed reducing gears, a brake disk actuated by said reduced gears, a brake cooperating with said disk, electrical means for releasing said brake and actuating the motor, automatic means for lowering and raising the seat, and for stopping both movements and applying said brake.

7. The combination, with a support, of a toilet seat mounted thereupon, an electric motor provided with speed reducing gears, a brake disk actuated by said reduced gears, a spring pressed brake cooperating with said disk, electrical means for releasing said brake and actuating the motor, automatic means for lowering and raising the seat, and for stopping both movements and applying said brake.

8. The combination, with a support, of a toilet seat fixed on a rotatable shaft mounted on the support, electrically propelled means, having a fixed, irreversible direction of rotary movement, and automatically actuated means for converting said rotary movement into alternating reversals, whereby the shaft is turned in one direction to lower partially the seat and in the opposite direction to raise it, and means functioning between reversals of the shaft to complete the lowering of the seat.

9. The combination, with a support, of a toilet seat hinged upon the support, electrically propelled means having an irreversible direction of rotary movement, and connecting means embodying a compound rocking bar having two commonly pivoted arms susceptible of limited relative movement for changing such rotary

movement into reversals to successively lower or raise the seat, the arms of the compound rocking bar yielding relatively to each other to prevent transmission of retrograde movement to the electrically propelled means.

10. The combination with a support of a partially rotatable shaft mounted thereon, a toilet seat fixed on said shaft, electrically propelled means having an irreversible direction of rotary movement, connecting means embodying a compound rocking bar and a piston rod for alternately reversing the direction of rotation of said shaft, a system of electrical conductors and switches, slideable and rockable switch controlling means, and means reciprocable by said compound rocking bar to actuate said switch controlling means, whereby the seat carrying shaft may be partially rotated alternately in opposite directions to raise and lower the seat.

11. The combination with a support of a partially rotatable shaft mounted thereon, a toilet seat fixed on said shaft, electrically propelled means having an irreversible direction of rotary movement, connecting means embodying a compound rocking bar and a piston rod for alternately reversing the direction of rotation of said shaft, a system of electrical conductors and switches arrangeable into a plurality of circuits to automatically carry out a cycle of operations, switch controlling means, and means reciprocable by said compound rocking bar to actuate said switch controlling means, whereby the seat carrying shaft may be partially rotated alternately in opposite directions to raise and lower the seat.

12. The combination with a support of a partially rotatable shaft mounted thereon, a toilet seat fixed on said shaft, electrically propelled means having an irreversible direction of rotary movement, connecting means embodying a compound rocking bar and a piston rod for alternately reversing the direction of rotation of said shaft, a system of electrical conductors and switches arrangeable into a plurality of circuits to automatically carry out a cycle of operations, switch controlling means, sterilizing means and means reciprocable by said compound rocking bar to actuate said switch controlling means, whereby the seat carrying shaft may be partially rotated alternately in opposite directions to raise, sterilize and lower the seat.

CYRIL T. KRENZER.
